Patented Oct. 28, 1890.

UNITED STATES PATENT OFFICE.

ZEFFIRO RIGALI, OF BOSTON, MASSACHUSETTS.

DESIGN FOR A PORTABLE NICHE FOR STATUARY.

SPECIFICATION forming part of Design No. 20,248, dated October 28, 1890.

Application filed June 4, 1890. Serial No. 354,285. Term of patent 7 years.

To all whom it may concern

Be it known that I, ZEFFIRO RIGALI, residing at Boston, in the county of Suffolk and State of Massachusetts, have invented 5 and produced a new and original Design for a Portable Niche for Statuary, of which the following is a specification, reference being had to the photograph forming part thereof.

The exterior is in the form of an oblong 10 square, surmounted by scroll-work and a cross and ornamented with oak-leaves arranged in this manner: On the front part of the frame, midway between the entrance to the interior and the outer edge, a raised bar 15 is placed on the sides and across the top. This bar is indented so as to show a hollow space, and upon the bar oak-leaves are intertwined so that the leaves fall across the space, while the stems form scallops, which are 20 turned toward the outer edges of the bar. A. Within the indentation on the bar small disks are placed and appear at intervals between the leaves. The space between the bar and the outer edge of the frame is cor- 25 rugated and overlaid with oak-leaves, their

stems forming scallops, which do not occur so frequently as on the bar; also, the scallops are turned all one way—toward the outside. The space between the bar and the entrance to the interior is plain. At the base 30 is a geometrical figure. The interior is concaved, B, save that part at the base, which is filled in with three steps, the upper one being circular in form.

What I claim is—

The design for a portable niche herein shown and described, the same comprising 35 the oblong - square - shaped exterior, surmounted by scroll-work and a cross and ornamented with oak-leaves and scallops, as set 40 forth.

In testimony whereof I have signed my name to this specification, in the presence of two subscribing witnesses, on this 3d day of May, A. D. 1890.

ZEFFIRO RIGALI.
